CLAIM

The ornamental design for a set of color icons for a portion of a display screen, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a set of color icons for a portion of a display screen showing our new design.

The broken lines illustrate portions of a display screen. The icons are arranged on the drawing sheet for the convenience of display. The broken lines and the arrangement of the icons form no part of the claimed design.
